UNITED STATES PATENT OFFICE.

WILLIAM F. MARTIN, OF BALDWINSVILLE, NEW YORK, ASSIGNOR TO PENN SPRING WORKS INC., OF BALDWINSVILLE, NEW YORK, A CORPORATION OF NEW YORK.

TIE-PLATE FOR AUTOMOBILE BUMPERS.

Application filed March 20, 1924. Serial No. 700,617.

To all whom it may concern:

Be it known that I, WILLIAM F. MARTIN, a citizen of the United States of America, and a resident of Baldwinsville, in the county of Onondaga, in the State of New York, have invented new and useful Improvements in Tie-Plates for Automobile Bumpers, of which the following, taken in connection with the accompanying drawings, is a full, clear, and exact description.

This invention relates to a tie plate for plural bar bumpers and more particularly, for securing a pair of spaced parallel bars to the return ends of an intermediate supporting bar whereby the spaced bars will be held in fixed relation to each other and to the intermediate bar.

The main object is to provide a sectional tie plate which will be at once ornamental as well as useful, and in which the sections are interlocked with each other, and with the bumper bars in such manner as to facilitate and expedite the assembling of those parts, and firmly holding them in their adjusted positions against relative vertical or longitudinal movement.

In bumpers of this character, it is desirable to bring the parallel bars in reasonably close, but spaced relation to the intermediate bar, and one of the specific objects of this tie plate is to interpose portions thereof, between the contiguous edges of the bars with a wedging effect when the sections are tightened so as to hold the adjacent portions of the bars against vibratory contact one against the other, and thereby to avoid the rattling noise common to many bumpers of the plural bar class.

Another object is to provide means for retaining the outer section upon the parallel bars even though the clamping bolt may be loosened.

Other objects and uses relating to specific parts of the device will be brought out in the following description.

In the drawings:—

Figure 1 is a face view of a plural bar bumper and a pair of my improved tie plates in operative position.

Figure 2 is an enlarged transverse vertical sectional view taken on line 2—2, Figure 1.

Figure 3 is an enlarged inner face view of

one of the tie plates and adjacent portions of the bars connected thereby.

Figures 4 and 5 are perspective views of the outer and inner sections respectively, of one of the tie plates.

As illustrated, the tie plate is used in connection with a pair of spaced parallel bars —A— and an intermediate supporting bar —B—, the ends of the bars —A— being secured in spaced relation by bolts —a— and spacing sleeves —a'—.

The intermediate bar —B— may be secured by any suitable fastening means to the chassis frame of the machine and is preferably disposed in a plane between and in spaced relation to the bars —A— and has its ends returned toward each other in the same vertical plane as the bars —A—, and in spaced relation thereto so that the return bends —b— are at substantially equal distances from the adjacent spacing sleeves —a'—.

The return ends of the intermediate bar —B— terminate in longitudinally spaced relation equal distances from the ends of the bars —A—, and therefore, some distance from the centers of those bars so that when connected to the bars —A—, they afford a certain amount of resiliency which together with that of the bars —A—, is found to be sufficient to meet the shock requirements of devices of this character with the added advantage of quick recovery without deformation, it being understood that the bars —A— and —B— are made of highly tempered spring steel.

The two tie plates shown in Figure 1 are identical and interchangeable and therefore, the description of one of them will answer for both.

As illustrated, each plate comprises an outer section —1—, an inner section —2— and clamping bolt —3—, the section —1— being extended vertically across the outer faces of the bars —A— and —B— while the inner section —2— extends across the inner faces of the same bars but is somewhat shorter than the section —1—.

The outer section —1— is gradually enlarged from the ends toward the center or reversely tapered from its center toward its ends, which latter are extended beyond the corresponding edges of the lower and upper

bars —A— and are provided with hook-shaped extremities embracing said edges to hold the section —1— against inward or outward displacement, while permitting its 5 adjustment along the bars —A— to and from the position required for fastening it in place.

In other words, the lower and upper ends of each plate —1— are provided with inwardly projecting horizontal portions —1'— engaging the adjacent edges of the bars —A— and are also provided with tongues or flanges —1''— extending toward each other for engaging the inner faces of said 10 bars at the outer sides of their longitudinal centers, the ends of the flanges —1''— being preferably rounded for the purpose of entering similarly formed recesses —2'— in the adjacent ends of the inner section —2— 15 and thereby locking the two sections together against relative lateral movement when the tie plate is adjusted for use.

The inner faces of the marginal edges of the plate —1— are substantially flat for the 20 purpose of engaging the outer faces of the bars —A— and —B— and, in cooperation with the flanges —1''—, holding the plate against forward and rearward vibratory movement relatively to the bumper bars.

30 The inner section —2— is provided with vertically spaced transverse ribs —4— registering with and adapted to enter the spaces between the intermediate bar —B— and lower and upper bars —A—, said ribs having their lower and upper faces beveled 35 outwardly so as to wedge against the adjacent edges of the bars —A— and —B— to firmly hold said bars against relative vibratory movement when the tie plate is properly tightened for use.

The inner plate —2— is also provided 40 near its lower and upper ends with outwardly projecting studs or pins —5— adapted to enter apertures —6— in the adjacent portions of the bars —A— for additionally holding said bars against relative

vibratory or longitudinal movement and also preventing rattling movement of the inner plate when properly tightened.

The clamping bolt —3— is passed 50 through registering apertures in the intermediate bar —B— and sections —1— and —2—, the shank of the bolt and opening in the section —1— being square to prevent turning of the bolt when clamping the sections upon the bars, the outer end of the bolt being rounded to form what may be termed an ornamental rosette —3'—, which together with the contour of the section —1— presents a pleasing and ornamental 55 appearance as set forth in my design application, Serial Number 9008, filed March 20, 1924, (Case B).

Owing to the hook-shaped extremities of the sections —1— they are preferably assembled upon the bars —A— before said bars are secured by the bolts —a— and spacing sleeves —a'— after which the end bolts —a— and spacing sleeves —a'— may be tightened thereby preventing accidental displacement of the sections —1— from the bars —A— even though they may become loosened from the intermediate bar —B—.

What I claim is:

1. An automobile bumper comprising 75 lower, upper and intermediate bars in spaced relation, and a tie plate section having beveled faces engaging between and against the adjacent edges of said bars.

2. An automobile bumper comprising 80 lower, upper and intermediate bars in spaced relation, and a tie plate section having beveled faces engaging between and against the adjacent edges of said bars, and also having pins engaging in apertures in 85 the lower and upper bars.

In witness whereof I have hereunto set my hand this 18th day of March, 1924.

WILLIAM F. MARTIN.
